WILLIAM N. WHITELEY, OF SPRINGFIELD, OHIO.

Letters Patent No. 99,506, dated February 1, 1870.

IMPROVEMENT IN RAKES FOR HARVESTERS.

The Schedule referred to in these Letters Patent and making part of the same.

To all whom it may concern:

Be it known that I, WILLIAM N. WHITELEY, of Springfield, in the county of Clark, and State of Ohio, have invented a new and useful Improvement in Rakes for Harvesters; and I do hereby declare the following to be a full, clear, and exact description of the same, reference being had to the accompanying drawings, in which—

Figure 1 is a perspective view of my invention attached to the platform of a harvesting-machine.

Figure 2 is an elevation of the rake-guide, from the rear, showing the switch-latch elevated.

Figure 3 is an elevation of the rake-guide, from the rear, showing the switch-latch depressed.

Figure 4 is a plan of the rake-shaft head.

Figure 5 represents the stop to prevent a displacement of the pivot-bolts in the rake-shaft head.

Figure 6 is an elevation of the rake-shaft and its attachments, in position, showing the switch in operation.

Figure 7 is a similar view, showing the switch thrown open.

Figure 8 represents the switch-piece detached.

Figures 9, 10, 11, 12, detached parts belonging to the switch.

Figure 13 is a vertical section, through rake-shaft, post-head, &c.

Figures 14 and 15 are plans of rake-guide, showing different positions of the switch.

Figures 16 and 17 are plans of the foot of the rake-post, showing its adjustments.

Figure 18 is a cross-section of the rake-blade.

This invention relates to the construction of the cam or guide and post, the two being cast solid in one piece instead of separately, as heretofore, and to the manner of adjusting the position of the cam and post.

That others may fully understand this invention, I will particularly describe it.

In fig. 1 is represented, in perspective, the platform of harvesting-machine attached to the finger-bar A, in the usual way, and the finger-bar A is bolted, at its inner end, to the inner shoe B.

The shoe B is provided, at its front and rear ends, with lugs C C, to which the ends of the bridge D are secured.

The post E is mounted upon the centre of the bridge D, and supports at its top the guide-cam F.

It has heretofore been customary to construct the guide-cam separate from the post, and make it adjustable thereon. This mode of construction is proved to be objectionable, because of the increased number of parts necessarily crowded into the small space presented by the area of the cam or guide. I therefore cast the post and cam-guide, solid in one piece, and provide the former with slotted lugs G, at its foot,

through which screws are inserted, to bind it to the bridge D, and at the same time permit a partial rotation on its axis as an adjustment. This is clearly shown in figs. 16 and 17. The adjustment referred to is made necessary to secure a proper position of the stroke of the rake when it descends upon the platform.

A stud, H, which is also a part of the post E, projects downward from the bottom of the said post, and protrudes through a hole made for that purpose in the bridge D, as shown in fig. 13, so that all lateral strains are received and resisted by said stud, instead of coming upon the binding-screws through the lugs G.

The lower end of the stud H also serves as a partial bearing for the driving-pulley I, as shown in fig. 13.

The post E is made hollow throughout its entire length, to receive the rake-shaft J, which has its bearings within said post. (See fig. 13)

At the lower end of said shaft is the pulley I, through which motion is communicated from the driving-mechanism to the rake and reel.

At the top of said shaft is a cast-iron head, K, having two projecting lugs, L L, on each of its four sides, to form part of the four rake and reel-arm joints, and supports the ends of the joint-bolts M M.

The lugs L L are connected at their upper edges by webs or flanges N N, two of which, diagonally opposite each other, are pierced with holes to receive the bolts O O, which, when in place, are interposed between the contiguous heads of the bolts M M, and prevent them from removing from their place, as clearly shown in figs. 1, 6, and 13. The bolts M are therefore made without other means of fastening.

The rake-arms P are mounted in cast-iron heads Q, which are jointed to the shaft-head K, between the lugs L, by the joint-bolts M.

Each one of the heads Q is made with two places to receive the arm K between them, and with a pendant arm, R, at the lower end of which the roller S is placed to bear upon and traverse the surface of the guide-cam F. These rollers are made of cast-iron, chilled in the mould, and are very durable.

The rake-blades T are formed with a curved flange, t, projecting upward and forward from the upper front edge, (see figs. 1 and 18,) and are provided with adjusting-braces U, by means of which the angle of blade to arm is regulated, to insure a proper parallelism between the blade and platform.

The guide-cam F is connected to the post E by arm f, and is cast solid therewith.

Its surface is that of a warped ring, equidistant at all points from an axial point, around which the rakes revolve, but with a general plane oblique to the axis of the shaft J.

The deflections of this surface are so arranged, that as the roller S traverses over it, they will cause the

rakes to move over the platform in a line parallel therewith, and during other parts of the circuit to rise up, so as to pass clear of the main frame, gearing, and driver upon his seat; and in order to prevent a removal of the rake from its proper course by an accidental jerk of the machine, or by contact with the standing grain as the rake descends toward and upon the front edge of the platform, the edge of the guide-cam F is extended, so as to form a flange, g, which is curved upward and backward, to cover the rollers S, as shown, and the guide-cam is thereby formed with a C-shaped cross-section, much more economical of material and strength than has hitherto been attained.

The blades T are all furnished with teeth, so that they may act indifferently as rakes or reels, but as it is not desirable that the gavel should be raked from the platform oftener than once during one revolution of the rake-shaft J, it is therefore necessary that means shall be provided to prevent the rake-blades from descending close to the platform when they should act only as reel-blades. This is accomplished by means of a switch, V, (see figs. 14 and 15) which may be opened to let the roller pass along the surface of the guide, and therefore the rake will descend upon the platform, or it may be closed to force the roller to pass over said switch, and raise the rake away from the platform, as shown in fig. 1.

The switch V has a short shaft, v, which descends through a suitable socket made in the guide-cam F, and it moves in said socket as a bearing.

The lower end of the shaft v is made square, for the reception of a cup, W, which receives and securely holds the lower end of the spiral spring X.

The upper end of said spring is secured in the loop a of the latch Y, and thereby is enabled to operate both the switch V and latch Y.

The latch Y is pivoted, at one end, to the stud b, which projects from the lower side of the guide-cam F, and extends thence across to a point in the vicinity of switch V, where the lip c will engage with the lug d, on the switch, as the latter is thrown open, to retain the switch in that position. The spring X thus acts in two directions, at right angles to each other. It causes the switch to revolve in a horizontal plane, while it also forces the latch Y upward, to engage with the lug d.

When the switch has been thrown open by the action of the spring X, it remains in that position (shown

in fig. 15) until the next succeeding reel-blade traveller S passes along the cam-way behind the switch, as shown in fig. 15.

Said roller S, as it advances, comes in contact with the tail e of the switch, which is thereby closed behind said roller, as shown in red lines in fig. 15.

When closed in this way, it is caught and held by the engagement of the latch Y and lug d, until such time as the latch shall be withdrawn by the act of the attendant, or by some automatic device attached to the apparatus. It is placed under control of the attendant by means of a cord, which may be attached to the latch, and thence passing under a roller, h, at the foot of the post E, is led to a position near to the attendant, and convenient to be operated by his hand or foot.

By means of said cord the latch may be tripped at any time, so as to permit the switch to open, and the next succeeding reel-blade will descend and sweep the grain from the platform. The attendant, however, will not find it necessary to control this action of the rakes, except when the grain to be cut is very thin upon the ground, or very irregular, as the stud i, attached by a screw or other means which admits of a ready removal, may be caused to release the latch Y at each revolution of the rake-shaft, and to this end the lower end of said stud is made with a bevelled surface, and adjusted so as to come in contact with the top or end of the stop y, which is a part of the latch Y, and serves also to limit the downward movement of said latch.

The hinged bridge-piece Z, located behind the switch V, serves to conduct the rollers S smoothly to the surface of the cam-guide F after said rollers have passed over the switch; and when one of said rollers passes behind said switch, the bridge-piece Z swings outward, to permit the roller to pass, as shown in fig. 15.

Having described my invention, What I claim as new, is—

1. The post E, cast in one piece with the guide-cam F, and secured by adjustable fastenings at the bottom, substantially as and for the purpose set forth.
2. The arrangement of the stud H, shaft J, and pulley I, as shown and described.

WM. N. WHITELEY.
